UNITED STATES PATENT OFFICE

125,292

DESIGN FOR A REFRIGERATED DISPLAY COUNTER

Irving W. Shell, Chicago, Ill.

Application December 16, 1940, Serial No. 97,352

Term of patent 14 years

To all whom it may concern:

Be it known that I, Irving W. Shell, a citizen of the United States of America, residing at Chicago, in the county of Cook and State of Illinois, have invented a new, original, and ornamental Design for Refrigerated Display Counters, of which the following is a specification, reference being had to the accompanying drawing, forming a part thereof.

Fig. 1 is a front perspective view of the refrigerated display counter, showing my design;

Fig. 2 is a rear elevational view, on a reduced scale; and

Fig. 3 is an end elevational view, also on a reduced scale.

I claim:

The ornamental design for a refrigerated display counter, as shown.

IRVING W. SHELL.
